UNITED STATES PATENT OFFICE.

ALBERT L. GALUSHA, OF DORCHESTER, MASSACHUSETTS.

POWER PLANT.

974,255.

Specification of Letters Patent. Patented Nov. 1, 1910.

Application filed March 11, 1909. Serial No. 482,849.

To all whom it may concern:

Be it known that I, ALBERT L. GALUSHA, of Dorchester, in the county of Suffolk and State of Massachusetts, have invented certain new and useful Improvements in Power Plants; and I do hereby declare the following to be a full, clear, and exact description of the invention, such as will enable others skilled in the art to which it appertains to make and use the same.

This invention relates to improvements in means for controlling the supply of fuel to an internal combustion engine.

One object of the invention is to provide means whereby the engine may be readily started.

A further object is to provide means whereby an internal combustion engine can be run with either producer gas or liquid fuel or changed from one to the other without stopping the engine.

A further object is to so construct and arrange the apparatus that draft may be furnished to "draw up" a gas producer fire and result in the making of good gas without the necessity for the use of a fan or exhauster or other such means.

A further object is to increase the power of an engine to be operated with producer gas, by enabling the engineer to enrich weak producer gas explosive mixture with more powerful mixture made from liquid fuel.

A further object is to provide means which will enable absolute and instantaneous control of the explosive mixture so that the engine may be supplied with producer gas alone; with the most powerful mixture that can be made with liquid fuel alone, or with explosive mixtures of producer gas and liquid fuel giving power intermediate of those of producer gas alone and liquid fuel alone.

A further object is to provide means which will enable a change from one ratio of gas mixture to liquid mixture to another ratio at any time.

A further object is to provide means which will prevent the valve which supplies liquid fuel from being opened beyond a certain limit and thus enable the use of high engine compression for producer gas and yet not get as high or too high compression for liquid fuel mixture.

A further object is to start a "producer gas internal combustion engine" easily, by providing at once an explosive mixture which can usually be made more easily at the

start from liquid fuel and air than from producer gas and air.

A further object is to provide means whereby the explosions can be made to continue and the engine kept running, although the mixture of air and producer gas may not be in proper condition to explode.

A further object is to completely control the power which the engine will give from "no load" to all the engine will carry, with the use of one valve, regardless of whether producer gas or liquid fuel is being used.

With these objects in view the invention consists in certain novel features of construction and combinations of parts as herein-after set forth and pointed out in the claims.

In the accompanying drawings, Figure 1 is a view of a plant with some of the parts in section, showing the application of my invention, and Figs. 2, 3, 4 and 5 are views showing different valve positions.

1 represents an internal combustion engine which in the present instance is shown as a three cylinder engine although my improvements are adaptable for use on other types of internal combustion engines.

2 represents a gas producer of any preferred construction and 3 a gas scrubber with which the outlet of the gas producer communicates through the medium of a pipe 4. A pipe or stack 5 communicates with the pipe 4 and at the intersection of these pipes, a three-way valve 6 is located and adapted to control the passage of gas from the producer to the scrubber or permit it to escape through the pipe or stack 5.

A pipe 7 communicates with the scrubber for conveying producer gas to the engine. This pipe is provided with a valve 8 and at a point in advance of this valve, the pipe 7 is connected by means of a pipe 9 with the inlet ports of the engine cylinders. At the intersection of the pipes 8 and 9 a three-way valve 10 is located and from this valve the pipe 7 is continued and communicates with a carbureter or vaporizer. Between the valve 10 and the carbureter or vaporizer 11, a valve 12 is located. A stop 13 is provided for the handle 14 of the valve 12 to prevent the latter from being opened beyond a predetermined extent, for reasons which will hereinafter appear. A pipe 15 communicates with the pipe 7 between the valves 8 and 10 for the purpose of conveying air into said pipe 7 to be mixed with the producer gas,—the space 16 of pipe 7 between

the valves 8 and 10 thus constituting a mixing chamber. The supply of air to this mixing chamber will be controlled by a valve 17 located in the pipe 15.

5 To start the engine, the valve 10 will be placed in the position shown in Fig. 3. This will close the passage of producer gas and air to the engine and open the passage for the supply of liquid fuel alone. Thus the 10 engine will be started in a manner similar to that employed with gasoline and other liquid fuel engines. The engine may be started with liquid fuel to the exclusion of producer gas and air with the valve 10 disposed as shown in Fig. 4 and the valves 8 and 17 closed.

For the purpose of "drawing up" the producer fire to improve the quality of the producer gas, (the engine being kept running by liquid fuel), the valve 6 will be moved to the position shown in Fig. 1 and the valve 10 to the position shown in Fig. 4. The 20 valves 8 and 17 (first the valve 8 and a little later the valve 17) will be gradually opened a little at a time. At first, smoke and poor gas simply dilutes liquid fuel charges going into the engine but as the producer gas improves, it, with air, will burn when air valve 17 is adjusted to supply a proper proportion 25 of air to the mixing chamber 16. As soon as the quality of gas will permit the valve 8 to be set in "running" position and valve 17 in position to give proper mixture of air, the operator will begin slowly to close the 30 throttle valve 12 and when the latter is practically closed the liquid fuel supply to the carburetor may be shut off. By leaving the valve 12 open a very little for a few minutes, the carburetor will be dried out and then the 35 valve 12 may be closed completely. The operator will now suddenly throw the valve 10 to the position shown in Fig. 1 and test position of valve 17 by slight changes until a mixture giving best results is obtained. The 40 liquid fuel supply being now cut off and the valves 8 and 17 open, the engine will be running with producer gas and the valves will be disposed approximately in the positions shown in Fig. 1, assuming that the 45 producer is of straight suction type. With gas pressure above atmospheric pressure, the positions of the valves 8 and 17 will be exchanged.

Should it be desired to use a more powerful explosive than can be provided by producer gas and air, or should the mixture of producer gas and air fall in quality, more or less liquid fuel may be mixed therewith and such result may be attained by manipulation 55 of the valve 10:—For instance said valve 10 may be disposed in the position shown in Fig. 5 when producer gas mixed with air and liquid fuel will enter the pipe 9, be intermixed therein and supplied to the engine 60 cylinder. It has been hereinbefore stated

that the stop 13 is to prevent the valve 12 from being opened too far. The reason for this is as follows: It is desirable to use perhaps 150 pounds per square inch compression in the engine cylinder for producer gas 70 but it is not safe to use over about 80 pounds compression with gasoline alone, because the heat of compression is liable to pre-ignite the gasoline. When the engine is made to give the right compression for producer gas 75 the partial closing of the valve 12 when running on liquid fuel reduces the amount of explosive mixture going to the engine and consequently the compression pressure or temperature maximum to a degree suitable 80 for liquid fuel.

Having fully described my invention what I claim as new and desire to secure by Letters-Patent, is,—

1. In apparatus of the character described, 85 the combination with an internal combustion engine, a gas producer, and a source of supply of liquid fuel, of a pipe connecting the gas producer and source of liquid fuel, a pipe connecting said first-mentioned pipe 90 with the engine, a three-way valve at the intersection of said pipes, a valve in the first-mentioned pipe between the three-way valve and the gas producer, and a valved air pipe communicating with the first-mentioned pipe between the said valves in the latter.

2. In apparatus of the character described, the combination with an internal combustion engine, a gas producer and a 100 vaporizer for liquid fuel, of a pipe connected with the gas producer and the vaporizer, a pipe connecting the first mentioned pipe with the cylinder of the engine, a three-way valve located at the intersection 105 of said pipes, a valve located between said three-way valve and the vaporizer, a valve located at the other side of the three-way valve, an air pipe communicating with the first mentioned pipe, and a valve in said air 110 pipe.

3. In apparatus of the character described, the combination with an internal combustion engine, a gas producer and a vaporizer for liquid fuel, of a pipe communicating at one end with the gas producer and at the other end with the vaporizer, a pipe connecting the first mentioned pipe with the engine cylinder, a three-way valve at the juncture of said pipes, a valve between the 115 three-way valve and the gas producer, the space between said valves constituting a mixing chamber, an air pipe communicating with said mixing chamber, a valve in said air pipe, and a valve between the three-way 120 valve and the vaporizer.

4. In apparatus of the character described, the combination with an internal combustion engine, and means for supplying producer gas and air to said engine, of a 125 130

vaporizer for liquid fuel, means of communication between the vaporizer and the engine cylinder, a valve in said means of communication, means for limiting the opening of said valve, and a three-way valve for controlling the passage of producer gas and air or liquid fuel separately to the engine cylinder or for permitting a mixture of producer gas and liquid fuel to pass to the engine cylinder.

5. In apparatus of the character described, the combination with an internal combustion engine, a gas producer, a pipe connecting the gas producer with the engine

cylinder, an air pipe communicating with 15 the first mentioned pipe, and valves in said pipes, of a stack adapted to communicate with the producer and a valve for opening said stack to the producer or for closing the latter and opening communication between 20 the producer and said first mentioned pipe.

In testimony whereof, I have signed this specification in the presence of two subscribing witnesses.

ALBERT L. GALUSHA.
